CLAIM

The ornamental design for telephone set, as shown and described.

DESCRIPTION

FIG. 1 is a front elevational view of a telephone set showing my new design;

FIG. 2 is a rear elevational view thereof;

FIGS. 3 and 4 are respectively right and left side elevational views thereof;

FIGS. 5 and 6 are respectively top and bottom plan views thereof;

FIG. 7 is a front perspective view of the set in assembled position with the handset cradled upon its stand; and

FIG. 8 is a similar front perspective view thereof with the handset inverted and spaced apart from the stand for clarity of representation of the handset and stand.

FIG. 1.

FIG. 2.

FIG. 3.

FIG. 4.

FIG. 5.

FIG. 6.

FIG. 7.

FIG. 8.
